(57) CLAIM

The ornamental design for a shower rod, as shown and described.

DESCRIPTION

FIG. 1 is a perspective view of a shower rod showing my new design;

FIG. 2 is an enlarged first end view of a stanchion for the shower rod;

FIG. 3 is a second end view of the stanchion;

FIG. 4 is a side view of the stanchion, the opposite side view being a mirror image of the side shown;

FIG. 5 is a top plan view thereof; and,

FIG. 6 is a bottom plan view thereof.

The stanchion element of the shower rod has been shown detached and fragmented for clarity of illustration.
